DESIGN FOR A BOTTLE

Georges Wilmet, Roslyn, N. Y., assignor to Distilled Liquors Corporation, New York, N. Y., a corporation of New York

Application March 12, 1940, Serial No. 90,861

Term of patent 14 years

To whom it may concern:

Be it known that I, Georges Wilmet, a citizen of Belgium, residing at Roslyn, county of Nassau and State of New York, have invented a new, original, and ornamental Design for a Bottle, of which the following is a specification, reference being had to the accompanying drawing forming a part thereof.

I claim:
The ornamental design for a bottle, as shown.
GEORGES WILMET.
